UNITED STATES PATENT OFFICE.

CARL L. YEARWOOD, OF KNOXVILLE, TENNESSEE.

BRUSH-HOLDER.

1,323,996.

Specification of Letters Patent.

Patented Dec. 2, 1919.

Application filed July 6, 1918. Serial No. 243,527.

To all whom it may concern:

Be it known that I, CARL L. YEARWOOD, a citizen of the United States, residing at Knoxville, in the county of Knox and State 5 of Tennessee, have invented new and useful Improvements in Brush-Holders, of which the following is a specification.

This invention relates to improvements in brush holders and aims to provide a convenient means by which a brush may be held 10 suspended in a receptacle with the bristles submerged in the paint, so as to prevent the brush from becoming dry and hardened and to hold the bristles from contact with the 15 bottom of the receptacle, which is especially desirable in marking brushes, which when the bristles bear the weight of the brush render the latter unfit for use.

To this end the invention includes a receptacle provided with a lid or cover, the latter carrying an arcuate shaped supporting member, to which is secured each end of a helical spring so as to bring its convolutions closer together on the side toward the center of the receptacle, thereby 25 affording a surer grip upon the handle of the brush.

The invention further consists of the following novel details of construction, combination and arrangement of parts to be 30 hereinafter more fully described and illustrated in the accompanying drawings.

In the drawings:

Figure 1 is a side elevation of the invention applied to a marking pot, the brush being shown supported in the holder;

Fig. 2 is a vertical sectional view of the same;

Fig. 3 is a plan view and

Fig. 4 is an elevation of the holder and lid removed from the pot.

The invention as illustrated in the accompanying drawings is shown as applied to an ordinary marking pot indicated at 10, 45 but it is of course understood that it is equally well adapted for use in connection with pots or receptacles of various shapes and sizes and it is desired that it be understood, that while for the purposes of illustration the marking pot is employed, the right is reserved to apply the invention in any manner for which it is adapted.

The pot 10 is provided with the usual handle 11 and also with the removable lid 55 or closure 12, the latter being provided with

a flange 13, which snugly fits the open end of the pot, so as to frictionally hold the lid in position. This lid is formed with an opening 14, through which access is obtained to the interior of the pot without 60 removing the lid. This opening extends from a point approximately central of the lid, to the edge or flange. Disposed transversely of the opening 14 at the outer end thereof and against the flange 13, is an arcuate shaped supporting member 15 which is vertically arranged and carries at its upper end a brush holding element. This latter is in the form of a helical spring 16, each end of which is threaded through 65 aligned apertures 17 located near each edge of the supporting member and its central portion is threaded through similar apertures 18 disposed substantially central of the width of the supporting member. This 70 holds the spring substantially the same line or curvature as the arcuate shaped supporting member, so that the convolutions of the spring on the side toward the center of the receptacle are brought closer together 75 than upon the opposite side. This securely holds the handle of the brush 19 in position between the convolutions by preventing the resilient character of the spring outward from the holder, as would likely occur if 80 the spring was arranged in a straight line.

It is believed that from the foregoing description and the accompanying drawings, that the operation and advantages of the invention will be apparent. The invention is 85 susceptible of various changes in its form, proportions and minor details of construction and the right is reserved to make such changes.

Having described the invention, what is 90 claimed is:

The combination with a receptacle, of a removable lid having an opening therein, a vertically disposed arcuate shaped supporting member arranged concentrically 100 with the receptacle and carried by the lid, a helical spring secured to said member and arranged substantially parallel with the lid and shaped to conform with the shape of the supporting member so as to bring the 105 convolutions closer together upon the side of the spring toward the center of the pan, to provide a brush holding element.

In testimony whereof I affix my signature.

CARL L. YEARWOOD.
